The ornamental design for ear bud, as shown and described.

DESCRIPTION

FIG. 1 is an isometric view of a first ear bud of a headset.
 FIG. 2 is a front view of the first ear bud of FIG. 1.
 FIG. 3 is a side view of the first ear bud of FIG. 1.
 FIG. 4 is an opposite side view of the first ear bud of FIG. 1.
 FIG. 5 is a back view of the first ear bud of FIG. 1.
 FIG. 6 is a top view of the first ear bud of FIG. 1.
 FIG. 7 is a bottom view of the first ear bud of FIG. 1.
 FIG. 8 is an off-angle view of the first ear bud of FIG. 1.
 FIG. 9 is another off-angle view of the first ear bud of FIG. 1.
 FIG. 10 is an isometric view of a second ear bud of the headset.
 FIG. 11 is a front view of the second ear bud of FIG. 10.
 FIG. 12 is a side view of the second ear bud of FIG. 10.
 FIG. 13 is an opposite side view of the second ear bud of FIG. 10.
 FIG. 14 is a back view of the second ear bud of FIG. 10.
 FIG. 15 is a top view of the second ear bud of FIG. 10.
 FIG. 16 is a bottom view of the second ear bud of FIG. 10.
 FIG. 17 is an off-angle view of the second ear bud of FIG. 10.
 FIG. 18 is another off-angle view of the second ear bud of FIG. 10.
 FIG. 19 is an exploded view of the first ear bud of FIG. 1 that features a gel cap (the annular-shaped piece), a wing (the pentagonal-shaped piece), and a bud; the gel cap and the wing are configured to be removable from the bud and the first ear bud, and the second ear bud are each configured to be placed at least partially inside a person's ear.
 FIG. 20 is another exploded view of the first ear bud of FIG. 1.
 FIG. 21 depicts an isometric view of the first ear bud of FIG. 1 with the gel cap removed; the cylindrical post that the gel cap normally mounts to is shorter in the following views than as depicted in FIGS. 19 and 20.
 FIG. 22 depicts a front view of the first ear bud of FIG. 21.
 FIG. 23 is a side view of the first ear bud of FIG. 21.
 FIG. 24 is an opposite side view of the first ear bud of FIG. 21.
 FIG. 25 is a back view of the first ear bud of FIG. 21.
 FIG. 26 is a top view of the first ear bud of FIG. 21.

FIG. 27 is a bottom view of the first ear bud of FIG. 21.
FIG. 28 is an off-angle view of the first ear bud of FIG. 21.
FIG. 29 is another off-angle view of the first ear bud of FIG. 21.

FIG. 30 is an isometric view of the second ear bud of FIG. 10 with the gel cap removed.

FIG. 31 is a front view of the second ear bud of FIG. 30.

FIG. 32 is a side view of the second ear bud of FIG. 30.
FIG. 33 is an opposite side view of the second ear bud of FIG. 30.

FIG. 34 is a back view of the second ear bud of FIG. 30.

FIG. 35 is a top view of the second ear bud of FIG. 30.

FIG. 36 is a bottom view of the second ear bud of FIG. 30.

FIG. 37 is an off-angle view of the second ear bud of FIG. 30; and,

FIG. 38 is another off-angle view of the second ear bud of FIG. 30.

Each of the ear bud in the accompanying figures, i.e., a first ear bud and a second ear bud, may be a part of a headset that may be placed, i.e., worn, in a person's ear.

Stipple shading is used in the accompanying Figures to convey surface contouring and not texture. The broken lines shown in the drawings illustrate portions of the ear bud that form no part of the claimed design; in such unclaimed portions the shading has also been removed.
